(57) **CLAIM**

The ornamental design for a “surveillance camera,” as shown and described.

DESCRIPTION

FIG. 1 is a front perspective view of a surveillance camera showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a front perspective view thereof; shown in an alternate position with the lens portion rotated in an upward position;

FIG. 9 is a front perspective view thereof; shown in an alternate position with the lens portion rotated towards the left side; and,

FIG. 10 is a front perspective view thereof; shown in an alternate position with the lens portion rotated towards the right side.

The broken lines depict portions of a surveillance camera in which the design is embodied and form no part of the claimed design.
